(57) ABSTRACT

A *Chrysanthemum* plant named 'Zanmuperfecor' characterized by its medium sized blooms with bronze ray florets and a dark center, and prolific branching; natural season flowering date September 9-14 (week 37); blooming for a period of 5 weeks.

3 Drawing Sheets

1

Botanical designation: *Chrysanthemum×morifolium* Ramat.
Cultivar denomination: 'Zanmuperfecor'.

RELATED CULTIVARS

This new plant a mutant obtained from the *Chrysanthemum* plant 'Zanmuperfect' (U.S. Plant Pat. No. 23,015).

BACKGROUND OF THE INVENTION

The present invention relates to a new and distinct cultivar of *Chrysanthemum* plant, botanically known as *Chrysanthemum×morifolium* Ramat., commercially known as a garden mum, and hereinafter referred to by the cultivar denomination 'Zanmuperfecor'. 'Zanmuperfecor' is a product of a breeding and selection program for outdoor pot mums (garden mums) which had the objective of finding color mutants from existing parent plants. The new plant comprises a whole plant mutation from the *Chrysanthemum* plant named 'Zanmuperfect'. Plants of the new cultivar 'Zanmuperfecor' differ from plants of the parent in the color of the inflorescences; the inflorescences are orange in 'Zanmuperfecor' and pink in 'Zanmuperfect'.

The new and distinct cultivar was discovered and selected as a flowering plant by Henricus Cornelius Maria Jacobs on a cultivated field in Rijsenhout, The Netherlands in 2007. The first act of asexual production of 'Zanmuperfecor' was accomplished when vegetative cuttings from the initial selection in 2007 were propagated further in a controlled environment in Rijsenhout, The Netherlands. In summer, about 6-8 days are needed to initiate roots in cuttings of the new cultivar, after another 5 days rooted plants are formed. The new cultivar has been found to retain its distinctive characteristics through successive propagations.

BRIEF DESCRIPTION OF THE DRAWINGS

The present invention of a new and distinct variety of *Chrysanthemum* (of about 16 weeks) is shown in the accom-

2

panying drawings, the color being as nearly true as possible with color photographs of this type.

FIG. 1 shows a plant of the cultivar in full bloom.

FIG. 2 shows the various stages of bloom of the new cultivar.

FIG. 3 shows the various stages of foliage of the new cultivar.

DESCRIPTION OF THE INVENTION

10 The observations and measurements were gathered from plants, in the period of 15 to 22 weeks of age, grown outdoor in Rijsenhout, The Netherlands, under natural day length and temperature and planted in week 23 in 2013 (with a warm summer), receiving drip irrigation. The natural blooming date of this crop was September 9-14 (week 37). The average height of the plants was 30 cm. No growth retardants were used. No tests were done on disease or insect resistance or susceptibility. No tests were done on cold or drought tolerance. This new variety produces medium sized blooms with bronze ray florets and a dark center blooming for a period of 5 weeks.

15 From the cultivars known to the inventor the most similar existing cultivar in comparison to 'Zanmuperfecor' is its parent 'Zanmuperfect' (U.S. Plant Pat. No. 23,015). When 'Zanmuperfecor' and 'Zanmuperfect' are being compared the following differences are noticed. (1). Color center inflorescences. And (2). Ray-floret color. (1). Inflorescences of 'Zanmuperfecor' have an orange center, while those of 'Zanmuperfect' have a red center. (2). Ray-florets of 'Zanmuperfecor' are bronze, while those of 'Zanmuperfect' are pink.

20 The following is a description of the plant and characteristics that distinguish 'Zanmuperfecor' as a new and distinct variety.

25 The color designations are taken from the plant itself. Accordingly, any discrepancies between the color designations and the colors depicted in the photographs are due to photographic tolerances. The color chart used in this description is: The Royal Horticultural Society Colour Chart, edition 2001.

TABLE 1

Botanical Description of *Chrysanthemum × morifolium* Ramat.
‘Zanmuperfecor’

Bud

Size:	Small; cross-section 6-8 mm, height 4-5 mm
Shape:	Round
Texture:	Pubescent
Outside color:	Greyed-green 191A
Phyllaries	

Number:	21-22, arranged in 3 rows
Shape:	Elliptic
Apex:	Acute
Base:	Truncate
Margin:	Entire
Color:	Upper side: Green 137A Lower side: Green N138C
Length and width:	8-10 mm; 2-3 mm
Texture:	Pubescent
Inflorescences	

Type:	Double
Height:	2 cm
Diameter:	5.5 cm
Peduncle length:	9.5-11 cm
Peduncle color:	Green 138C
Peduncle diameter:	2 mm
Peduncle texture:	Pubescent
Peduncle strength:	Weak
Number per branch:	About. 5-7 inflorescences
Duration of flowering:	5 weeks
Seeds:	Produced in small quantities, ovate, Greyed-brown 199A, length 1.5 mm, diameter 0.5 mm; structure: rough with ribs
Fragrance:	Faint <i>chrysanthemum</i> odor
Color inflorescences	

Center of inflorescence:	Immature stage: Greyed-orange 173A; Mature stage: Greyed-orange 173A
Color of upper side of ray florets:	Greyed-orange 166C
Color of lower side of ray florets:	Greyed-orange 165C
Tonality from distance:	A garden <i>mum</i> with bronze blooms and a dark center
Color of ray florets after aging of the plant:	Greyed-orange 164C
Ray florets	

Type:	Ligulate
Texture:	Upper and lower side smooth
Number:	170-180
Shape:	elliptic
Apex:	dentate
Base:	acute
Cross-section:	flat
Longitudinal axis:	straight
Length of corolla tube:	3-4 mm
Diameter corolla tube:	1 mm
Ray floret margin:	Entire
Ray floret length:	1.7-2.7 cm
Ray floret width:	2-4 mm
Ratio length/width:	High
Disc florets	absent
Receptacle	

Color:	Yellow-green 145D
Shape:	Domed raised
Height:	3 mm
Diameter:	3 mm
Reproductive Organs	

Androecium:	absent
Pollen:	absent
Gynoecium:	Present on ray florets
Style color:	Yellow-green 154C
Style length:	4 mm

4

TABLE 1-continued

I claim:

60

1. A new and distinct *Chrysanthemum* plant named 'Zan-muperfecor' as described and illustrated.

FIG. 1

FIG. 2

FIG. 3
